US00D968955S

(12) **United States Design Patent** (10) **Patent No.:** **US D968,955 S**
Cernokus et al. (45) **Date of Patent:** **** Nov. 8, 2022**

(54) **PACKAGING**(71) Applicant: **Apple Inc.**, Cupertino, CA (US)(72) Inventors: **Evan Cernokus**, Campbell, CA (US);
Mark T. Uyeda, Campbell, CA (US)(73) Assignee: **Apple Inc.**, Cupertino, CA (US)(***) Term: **15 Years**(21) Appl. No.: **29/830,136**(22) Filed: **Mar. 10, 2022****Related U.S. Application Data**

(63) Continuation of application No. 29/807,541, filed on Sep. 13, 2021, now Pat. No. Des. 947,024, which is a continuation of application No. 29/758,348, filed on Nov. 13, 2020, now Pat. No. Des. 930,477, which is a continuation of application No. 29/734,868, filed on May 15, 2020, now Pat. No. Des. 902,032, which is a continuation of application No. 29/706,854, filed on Sep. 24, 2019, now Pat. No. Des. 884,470, which is a continuation of application No. 29/618,870, filed on Sep. 25, 2017, now Pat. No. Des. 861,497, which is a continuation of application No. 29/598,108, filed on Mar. 23, 2017, now Pat. No. Des. 806,537, which is a continuation of application No. 29/523,465, filed on Apr. 9, 2015, now Pat. No. Des. 789,800.

Primary Examiner — Lauren R Calve*(74) Attorney, Agent, or Firm* — Sterne, Kessler,
Goldstein & Fox P.L.L.C.(57) **CLAIM**

The ornamental design for packaging, as shown and described.

DESCRIPTION

FIG. 1 is a bottom front perspective view of packaging showing the claimed design;

FIG. 2 is a bottom view thereof;

FIG. 3 is a top view thereof;

FIG. 4 is a left side view thereof;

FIG. 5 is a right side view thereof; and,

FIG. 6 is a front view thereof.

The broken lines in the figures show portions of the packaging that form no part of the claimed design.
